United States Patent Office.

LANCELOT HOPE EVERITT, OF NEW ORLEANS, LOUISIANA.

Letters Patent No. 75,886, dated March 24, 1868.

IMPROVEMENT IN ACOUSTIC TELEGRAPHING.

The Schedule referred to in these Letters Patent and making part of the same.

Be it known that I, LANCELOT HOPE EVERITT, of New Orleans, in the parish of Orleans, and State of Louisiana, have invented a new and useful Machine for Acoustic Telegraphing long distances; and I do hereby declare that the following is a full, clear, and exact description of the construction and operation of the same, reference being had to the annexed drawings, making a part of this specification, in which—

Figure 3 is a vertical section of the base, A A', the incus B, the nipple of the incus, I, the stapes G, the rings of metal H H' H H', surrounding the anterior and posterior parts of the incus; the auricular K; the hélix L; the anterior cochlea M; the vestibule N; the posterior cochlea O; the acoustic messenger α α' ; and the diatonic staff P, supporting two bars marked 1 and 2, representing the two different distances of strike from the incus, marked by red and blue-colored disks, respectively, by means of which the different orders of sound are created and governed.

Figure 2 is a vertical section of the *chorda tympani* E, of the malleus C, of the phonic fossa D, and the key F, by which the machine is worked; and No. 1 represents the symbolic formula of the vowel order of sounds; No. 2, the symbolic formula of the aspirate order of sounds, constituting the two primary orders of sound, which, together, evolve the symbolic formula of the fulcimen order of sound No. 3, the symbolic formula of the bifulcimen order of sound No. 4, and the formula of the valorem order of sound No. 5, representing all the letters of the English alphabet and all the Arabic notations.

Figure 1 is a perspective view of the acoustic battery.

To enable others skilled in physics to make and use my invention, I will proceed to describe the nature, construction, and operation of the machine, and the symbolic formula of letters and notations which govern its operations, and how they are expressed by similar and dissimilar sounds.

The different tones of sound are evoked from the atoms of the atmospheric air by metallic machinery, and are arranged under five different orders, which, when sounded in a manner hereafter to be described, express all the letters of the alphabet and every notation. These are created, reflected, and transmitted through thick, naked, non-insulated brass or other wire buried in the earth or water, which conveys them to distant parts, and thus rapidly communicates intelligence afar off. Hence the machine is called the Acoustic Battery; and the nature of its operations has given it the name of the Acoustic Telegraph. For the purpose of describing all its parts, I have used anatomical terms, describing the anatomy of the ear, and employed red and blue-colored disks and a diatonic staff to give a tangible and practical idea of its mechanism and varied operations.

Upon the marble base A A' the acoustic battery is placed and firmly fixed. B is a solid cylinder of bell-metal, named the incus. Its face forms the *point d'appui* upon which the different sounds are evoked, and the body of the incus conducts them to its nipple I, which transmits them to the acoustic messenger α . C is the malleus, made of solid brass metal, through the facial surface of which an elliptical opening is drilled from before backward. This forms the phonic fossa D, which is highly polished, and when the facial malleus is struck upon the facial incus, the sounds thus evoked are reflected from its surface and impelled through the incus to the acoustic messenger, which conducts them to its distal extremity. E is the *chorda tympani*, made of an elongated spring-steel, the sixteenth part of an inch thick or more, and half an inch broad, curved above, where it is fitted and fastened into the top of the stapes G, and curved below so as to form the key F, and near its lower third it is inserted into the head of the malleus and permanently secured therein. Its actions are to elicit sound from the atmospheric atoms, as herein described, and incepts the initial momentum of sound. G is the stapes, made of brass metal. It is mounted over the facial incus, and securely fastened by projecting feet into the marble base A. It supports the *chorda tympani*, key, and malleus, and gives direction and efficiency to their required actions. H H' and H H' are rings cast in brass metal two-eighths of an inch thick and broad, with extending arms, which encircle the face and nipple of the incus, and hold firmly the incus within the semi-circular excavation made in the marble base for its reception. I is the nipple, formed out of the solid body of the incus. A hole one inch deep, and large enough to receive the end of the acoustic messenger, is drilled in its centre, and a side-screw so fitted as to hold the end of the wire firmly while the operator is sending his message.

O is the posterior cochlea, formed out of the solid vestibule N. In this, also, a hole one inch deep, and fitted with a side-screw, is so arranged as to hold firmly the end of the wire while the auditor is receiving his message. M is the anterior cochlea, formed similar to the other, in which a hole is drilled for the permanent reception of the helix L, and which conduct sounds from the vestibule to the auricular K, and this delivers them to the ear of the auditor in the exact order in which they are sent by the operator. P is the diatonic staff, which supports two metallic bars, 1 and 2. The outer point of the first bar is placed one-sixteenth of an inch from the facial incus, and when the face of the malleus is drawn to this point, and made to suddenly strike the face of the incus, the soft or vowel order of sound is created. The outer point of the second bar is three-eighths of an inch from the facial incus; and from this point the sharp or aspirate order of sound is generated, and together they form the two primary orders of sound. These being separated by silent intervals, graduated by spaces of time, and combined in various ways, give origin to symbolic formulae, expressive of all the letters of the English alphabet and all Arabic notations, and, being variously arranged, they constitute other orders of sound, as the following examples will explain, reference being made to the illustrations upon the drawings, and the numbers attached thereto:

No. 1 is the vowel order of sound, denoted by red-colored disks, and two such, when sounded from the first bar, denote the letter A; three such express the letter E; and so on of the other vowels.

No. 2 is the aspirate order of sound, distinguished by blue-colored disks, and two such, when sounded from the second bar, represent the letter H; three such form the letter L; and so on of the other letters arranged under this order.

No. 3 is the fulcimen order of sound, characterized by a union of red and blue disks, and when one of each is sounded conjointly, and directly after the other, the letter F is formed; when one red and two blue are thus sounded, the letter S is produced; and so on of other letters under this order sounded according to their symbolic formula.

No. 4 is the bifulcimen order of sound, formed by the union of blue and red disks, and when sounded in a similar manner, they express all the letters placed under this order.

No. 5 is the valorem order of sound, expressing valuation by means of numbers. It is formed by a commingling of red and blue disks, so as to constitute symbolic formulae peculiar to themselves to prevent mistakes in telegraphing numbers; and when sounded in this order they express any simple or compound numbers that cannot be mistaken for letters.

The following instructions specify the mode of telegraphing between distant points of communication: Two acoustic batteries are connected together by means of thick, naked, non-insulated brass wire buried in the land or water, and separated from each other, from A to Z, the message being sent from the former to the latter. The operator at A places the end of his wire within the nipple of the incus, and firmly screws it therein. The auditor at Z places the end of his wire within the posterior cochlea, so as to be in direct contact with the body of the vestibule, and screws it in tightly. Ten sounds of the aspirate order are struck off by the operator, which, being returned by the auditor, signifies that he awaits the message. If the auditor has a good retentive memory, he receives the various symbols, separates and combines them in the order they are sent, and easily converts them into letters, words, sentences, and notations. The whole message being sent, ten aspirate sounds, sent directly after, denote this fact to the auditor. The acoustic messenger at each end of the line of communication is then reversed, so that the auditor becomes operator, and *vice versa*. If a message is going to be returned, this is indicated by eight aspirate sounds; if not, twelve such sounds will carry that information. Soft and sharp sounds travel through naked wire with equal velocity, and when evoked and transmitted to the distant auditor by means of the acoustic battery, they resemble the twits and chirps of birds near and from afar, and the one is so dissimilar from the other that mistakes are next to impossible in constructing the symbolic formula of any letter or notation, as their express sounds leap from the end of the auricular.

What I claim as my invention, and desire to secure by Letters Patent, is—

An acoustic battery for telegraphing, a machine which creates and modulates sounds, that, when arranged and sounded under specific symbolic formulae, they are made to represent and express all the letters of the English alphabet and all Arabic notations, and when thus evoked into existence the machine reflects these sounds and transmits them through naked wire, buried in the land or water, to their destination, where they impart their various interpretations with such distinctness and order to the auditor who receives them, as to become the most important and efficient commissioners of intelligence.

I claim, also, and desire to secure within these Letters Patent, this mode of eliciting two different tones of sound from the air, by means of the *chorda tympani*, the malleus, the key, the incus, the stapes; of reflecting them from the polished phonic fossa; of conducting them to the acoustic messenger through the nipple of the incus, and transmitting them through non-insulated wire to the cochlea, vestibule, and auricular, which delivers them to the auditor with precision and regularity.

I claim, also, and desire to secure within these Letters Patent, this mode of associating these two modulated tones, and arranging them under five different orders of sound, expressive of letters and notations, as herein described, and this method of using similar and dissimilar silent intervals of time in separating and combining sounds, thus giving force and decided character to the symbolic formula of a letter or notation when echoed from the phonic fossa and transmitted through naked wire to the end of the auricula.

I claim, also, and desire to secure within these Letters Patent, this mode of creating and regulating these two primary orders of sound, and other orders evolved from them, systematically, by means of a diatonic staff and two bars attached thereto, and signalizing different sounds by red and blue-colored disks, which represent

two very dissimilar tones that are convertible into intelligent symbols, as herein described, or by any other means substantially the same, and which will produce the intended effect.
